UNITED STATES PATENT OFFICE.

JAMES DUVALL, OF CAMAS, WASHINGTON.

ROLL-TIGHTENING MACHINE.

1,164,586.

Specification of Letters Patent. Patented Dec. 14, 1915.

Application filed April 23, 1915. Serial No. 23,529.

To all whom it may concern:

Be it known that I, JAMES DUVALL, a citizen of the United States, and a resident of Camas, Clarke county, Washington, have 5 invented a new and useful Improvement in Roll-Tightening Machines, of which the following is a specification.

My invention relates to devices to be used for tightening rolls of paper or other material, and it is particularly designed for 10 winding up toilet paper into compact rolls of uniform size.

As well known, the strip of toilet paper is fastened at its initial end to a hollow 15 paper core, and since the material has low tensile strength, the roll must necessarily be wound rather loose, in order to prevent the breaking of the strip. But the rolls so obtained are too loose for practical purposes, 20 and so it is found desirable that they be rewound into a more compact form, in order to facilitate handling and packing.

To this end, one of the main objects of my 25 invention is to provide a machine which will automatically rewind the roll from within, and the device which I have provided for this purpose comprises the combination of a rotatable shaft, adapted to receive a hollow-core roll, means for intermittently 30 rotating the shaft, means for exerting a hold on the interior of the hollow core of the roll placed on the shaft, to thereby prevent the rotation of the core about the shaft, but nevertheless permitting it longitudinal 35 movement on the latter, as required for placing the roll on the shaft, and removing it therefrom; and means for exerting a frictional hold on the exterior of the roll mounted on the shaft, while such roll is in its 40 normal state, but releasing such hold when the roll is rewound in such compact form as to reduce the same to a predetermined diameter.

The details of the mechanical means which 45 are so combined in my machine, and the operation of the latter, are fully illustrated in the accompanying drawings, in which,

Figure 1 is a side elevation of my machine; the spring friction arm which holds 50 the roll against rotation being shown in section; Fig. 2 is a vertical sectional elevation of the parts shown in Fig. 1; Fig. 3

is a plan view of the top of my machine; Fig. 4 is a larger sized fragmental vertical section of the mandrel on which the roll 55 is mounted. The core of the roll is shown in section so as to illustrate the manner in which the mandrel grips said core, so as to prevent rotation of the core relative to said mandrel; Fig. 5 is a horizontal section taken 60 on the line 5—5 of Fig. 4; the core being shown in broken outline; Fig. 6 is a larger sized horizontal section showing the details of the friction gear operating mechanism; Fig. 7 is a vertical section taken approxi- 65 mately on the line 7—7 of Figs. 2 and 6; and Fig. 8 is a detail view of the sleeve provided with a cam slot, by means of which the friction gear is thrown into operative state.

In the drawings, *a*, *a'* represent the side 70 frame members of my machine; *b* is a top-plate provided with a vertically projecting hub *c*, and *d* is a bracket provided with the bearing arms *e*, *f*, and *g*, said bracket *d* being bolted to the frame member *a'*. See 75 Fig. 2. Bolted to the frame member *a* is a bracket *h*, provided with a bearing-hub *i*, the latter being in axial alinement with the bearing arm *g*, of the bracket *d*. A radial stud-pin *j*, projects internally in the hub *i*. 80 See Figs. 2, 6, 7 and 8. A sleeve *k*, made with an integral lever arm *l*, is provided with a helical, peripheral cam slot *m*, through which the stud-pin *j*, projects. Said sleeve is rotatably journaled in the hub 85 *i*, and the rotation of said sleeve *k*, will cause the latter to move longitudinally to the position shown in the broken lines of Fig. 8. This movement is due to the cam action produced by the slot *m*, working on 90 the fixed stud-pin *j*. A foot-lever *n*, pivotally mounted on the stud *o*, in the frame *a*, is connected to the lever arm *l*, by a link *p*. A spring *q*, normally holds the parts in the position shown in the full lines of Figs. 1 95 and 8. A constantly driven shaft *r* is rotatably mounted in the bearing arm *g*, and the sleeve *k*, said shaft being reciprocable in the bearing *g*. On the outer end of the shaft *r*, adjacent the sleeve *k*, is setscrewed a 100 collar *s*, and pinned on the shaft adjacent the other end of the sleeve *k*, and located between the two frame members *a*, *a'*, is a friction gear *t*. By reason of this construc-

tion, a depression of the foot-pedal *n*, will cause the shaft *r*, and thereby the friction-gear *t*, to be displaced longitudinally along the axial line of said shaft *r*. The shaft *r* is continuously driven by means which are not shown in these drawings. The bearing arms *e* and *f* of the bracket *d* are in vertical alinement with the hub *c*, and rotatably journaled therein is a vertical shaft *u*. A friction pinion *v* is adjustably fixed on said shaft *u*, by means of a set-screw *w*, and the slot *x*. This adjustment allows the speed of rotation of the shaft *u* to be regulated. The upper end of the shaft *u* is provided with a collar *y*, seated in a recess *z* of the top plate *b*, which collar prevents the shaft *y* from vertical displacement downwardly. The collar *z* fixed on the shaft and bearing against the lower face of the hub *c*, prevents the shaft *u* from vertical displacement upwardly. The mandrel *4*, located above the top plate *b*, is an integral part of the shaft *u*. Said mandrel is provided with a rounded top *8*, to facilitate the placing of the rolls thereon. Said mandrel *4* is further provided with a diametric slot *9*, in which are mounted gripper wheels *10*, the peripheries of which are serrated so as to form the teeth *11*. Said wheels *10*, are rotatably mounted on the bearing pins *12*, which are fixed in the mandrel and the ends of which are rounded off so as to conform with the cylindrical surface of said mandrel. It is to be noted that the circular grippers *10* permit the core *18* to move longitudinally of the mandrel, but prevent rotary movement relative thereto.

On the top *b*, of the frame, are the vertical studs *13*, on which is fixed a spring cylindrical arm *14*. See Fig. 3. A series of holes *15* are provided in the face of the top *b*, and are adapted to hold a stop pin *16*, against which the spring arm *14* contacts, when the roll has been reduced to a predetermined size.

17 represents a roll of toilet-paper and 18 is a paste-board core upon which said roll is wound.

The operation of my machine is as follows: When the machine is in its inactive state, the coil spring *q* will hold all parts in the position shown in Figs. 1 and 2. It will thus be seen by having reference to Fig. 2 that the friction drive gear *t* will be out of engagement with the friction pinion *v*, and the mandrel *4* will thereupon be stationary. The roll of toilet paper *17*, is then placed upon the mandrel *4*, being then thrust down over the circular gripper wheels *10*, and the teeth of the latter will bite into the body of the core and hold it against rotation relative to said mandrel. The spring arm *14* is then placed around the roll *17* and the stop pin *16* adjusted to one of the holes *15*, de-

pending on the size to which the roll is to be reduced. The foot-pedal *n*, is then depressed so as to throw the friction drive gear *t* into engagement with the pinion *v*, thereby driving the mandrel in a rotary direction. The tension of the spring arm *14* will exert a frictional resistance which will hold the outside of said roll stationary and the rotating mandrel will wind the core *18* within the roll, thereby tightening the paper and reducing the roll to a smaller diameter. When the reduction of the roll to the proper diameter has been reached, the spring arm *14* will contact with the stop pin *16*, the frictional resistance of said arm to the roll will be destroyed, and the roll will be held against further tightening. After the tightening process has been completed, the foot-pedal *n*, is allowed to resume its normal position, whereupon the machine will be replaced to its inactive state. The roll may be readily removed from the mandrel.

I claim:

1. In a device of the character described, the combination of a rotatable shaft adapted for receiving a hollow-core roll, such shaft formed with a recess, a vertical circular gripper-element journaled in such recess projecting beyond the periphery of the shaft, and being rotatable in a longitudinal plane of the latter, means for exerting a frictional hold on the exterior of the roll mounted on the shaft, and other means adapted to release such hold when the roll is reduced below a predetermined diameter.

2. In a device of the character described, the combination of a rotatable shaft adapted for receiving a hollow-core roll, such shaft formed with a recess, a vertical circular gripper-element journaled in such recess projecting beyond the periphery of the shaft, and being rotatable in a longitudinal plane of the latter, means for exerting a frictional hold on the exterior of the roll mounted on the shaft, and other adjustable means adapted to release such hold when the roll is reduced below a predetermined diameter.

3. In a device of the character described, the combination of a rotatable shaft adapted for receiving a hollow-core roll, such shaft formed with a recess, a vertical circular gripper-element journaled in such recess projecting beyond the periphery of the shaft, and being rotatable in the longitudinal plane of the latter, a resilient arm fastened at one end adjacent to the shaft, such arm adapted to encircle the roll mounted on the shaft, and to contract its diameter normally, and means for limiting said contraction of the resilient arm.

4. In a device of the character described, the combination of a rotatable shaft adapted for receiving a hollow-core roll, such shaft

formed with a recess, a vertical circular gripper-element journaled in such recess projecting beyond the periphery of the shaft, and being rotatable in a longitudinal plane 5 of the latter, a resilient arm fastened at one end adjacent to the shaft, such arm adapted to encircle the roll mounted on the shaft, and

to contract its diameter normally, and adjustable means for limiting said contraction of the resilient arm.

JAMES DUVALL.
